UNITED STATES PATENT OFFICE.

PETER SCHMIDT, OF ST. LOUIS, MISSOURI, ASSIGNOR TO DURBIN AUTOMATIC TRAIN PIPE CONNECTOR COMPANY, OF ST. LOUIS, MISSOURI, A CORPORATION OF ARIZONA.

LOCKING MECHANISM FOR TRAIN-PIPE COUPLINGS.

1,092,296.

Specification of Letters Patent.

Patented Apr. 7, 1914.

Application filed January 6, 1913. Serial No. 740,381.

To all whom it may concern:

Be it known that I, PETER SCHMIDT, a citizen of the United States, residing in the city of St. Louis and State of Missouri, have 5 invented new and useful Improvements in Locking Mechanism for Train-Pipe Couplers, of which the following is a specification.

This invention relates to certain new and 10 useful improvements in train pipe couplers, and has particular reference to an automatic locking means for use with the construction of coupler invented by Votaw S. Durbin, and forming the subject-matter 15 of an application, Serial No. 740,313 filed of even date herewith.

The object of the invention is to provide 20 an improved locking device which will act to automatically lock the two coupler heads together, and will maintain them in such interlocked relation irrespective of the positions to which they may be turned in service, and which will automatically be turned to release the coupler heads to permit them 25 to be separated when the cars are drawn apart.

The invention is illustrated in the accompanying drawings, in which—

Figure 1 is a view in side elevation showing 30 two interlocked train pipe couplers, and illustrating the application of my invention; Fig. 2 is a plan view of the same; Fig. 3 is a broken plan view of a single coupling member, showing my improved locking device in the uncoupled position; Fig. 4 is a view partly in section and partly in elevation of the rear portion of the locking device, or that part shown at the left of the preceding figures; and Fig. 5 is a view in 40 rear elevation of the same.

Referring now to the drawings, the numerals 1, 2, indicate two interlocked train pipe coupler heads. Each coupler head is provided on its rear side with a projection 45 3 which is pivotally mounted in the outer end of a hollow plunger 4 by means of a pivot pin 5. The numeral 6 indicates a bracket which is provided with a flanged top 7 suitably shaped and apertured where-

by it may be securely fastened to frame 50 members 8 depending from the car body. Two converging legs or webs 9 of the bracket are bifurcated in their lower portion to form yokes, the arms 10, 11, of which straddle the plunger 4 and at their point of 55 convergence on either side of said plunger the said yokes are provided with an aperture through which passes a pivot pin 12, which pivot pin likewise extends through slots 13 formed in opposite sides of the plunger 4 at the rear end thereof. Mounted in the plunger is a coil spring 14, the forward end of which is engaged by the inner end of the plunger 4, as shown in the application of Durbin above referred to, and the 60 rear end of which encircles and rests against a headed sleeve 15. The headed end of the sleeve 15 rests against pivot pin 12. Normally the coupler heads 1 and 2 project 65 some distance beyond the face of the respective car coupler heads so that they are brought into engagement before the car couplers. As the coupler heads 1 and 2 are thus brought together the plunger 4 is 70 pressed backward against the resistance of 75 the spring 14, the slot 13 riding over the pivot pin 12. During the time, therefore, that the said coupler heads are in interlocked relation the spring 14 of each plunger is exerting its force to maintain a firm 80 contact between the meeting surfaces of the two heads. In order to prevent the accidental separation of the coupler heads 1 and 2 I provide the automatic locking 85 means forming the subject-matter of the present invention, and now to be described.

As shown by Figs. 2 and 3 each coupler head is provided with a pyramidal projection 16 and with an opening 17, which latter is designed to receive the corresponding pyramidal projection on the companion coupler head. The pyramidal projections 16 are hollow, and pivotally mounted at 18 on the inner side of each coupler head is a lock-lever 19 having a hook 20 which is adapted 90 to project through an opening 21 in the wall of the projection 16 and to engage over the top 22 surrounding the opening 17 of the 95

companion coupler head. Pivotally secured at 23 to the outer end of the lever 19 is a rod 24, the rear end of which is pivotally connected at 25 to the outer end of a link 5 arm 26 which extends outward at right angles to a vertically disposed pin 27 which is mounted at the extreme inner end of the plunger 4, the said inner end of the plunger being cut away, as indicated at 28, to provide a space for the play of the arm 26. The arm 26 has a hub 29 which is rotatably mounted on the pin 27. The numeral 30 indicates a coil spring which encircles the pin 27 and has one end 31 secured in the 10 end of the plunger 4, and its other end 32 bearing against the arm 26 in such manner as to tend normally to press the rod 24 inward, or to the position it is shown to occupy in Fig. 2, thereby forcing the hook 20 through the opening 21. Formed integral with the bracket 6, and projecting from the rear side thereof, is a lug 33 which in 15 operation is adapted to engage the inner side of the arm 26. This occurs when the cars 20 are separated. In such operation the bracket 6 will, of course, first be moved backward by the car and in such movement the lug 33 will strike the arm 26 and draw the rod 24 backward, thereby turning the 25 hook 20 out of engagement with the rim 22 so that in the continued operating movement of the cars the two coupler heads 1 and 2 may be drawn apart. As these coupler heads are brought together the plunger 4 30 is forced backward, carrying the arm 26 out of engagement with the lug 33 and permitting the spring 30 to again force the rod 24 forward or toward the coupler heads to turn the hook 20 outward and into engagement 35 with the rim 22. In the interlocked position of the coupler heads it will be seen that the movement thereof about their pivots 5 will not in any manner tend to change the position of the hook 20 relative to the coupler 40 heads, for the reason that in the locked position the lock-lever 19 is constantly subject to the tension of the spring 30 through the medium of the rod 24 so that said spring 45 will always automatically compensate for any movement which would tend to turn the lock-lever from its position.

While in actual operation the construction of locking mechanism herein shown has been found to be accurate and reliable, and 50 is the best form of the invention now known to me, I wish it to be understood that I do not limit myself to the precise details of the construction shown, as it is obvious that the same could be modified in various ways 55 without departing from the broad idea illustrated, of an automatic locking device maintained under constant spring pressure whereby it is not affected by movement of the coupler heads.

I claim:

1. In a train pipe coupler, in combination with a spring-pressed plunger carried by the car and having a coupler head, a locking device pivotally mounted on the head, link mechanism pivotally connected with 70 said plunger and said locking device, means carried by the car for causing the link mechanism to release the locking device in the separating movement of the cars, and a spring tending normally to actuate the said 75 link mechanism to force said device into locking position.

2. In a train pipe coupler, in combination with a spring-pressed plunger carried by the car and having a pivoted coupler head, 80 a locking device pivotally mounted on the head, link mechanism pivotally connected with said plunger and said locking device, a spring tending normally to actuate said 85 link mechanism to force said device into locking position, and a lug carried by the car and adapted to engage the link mechanism and cause it to release the locking device in the separating movement of the 90 cars.

3. In a train pipe coupler, in combination with a spring-pressed plunger carried by the car and having a pivoted coupler head, a pivoted locking member mounted on the head, a spring pressed link pivotally mounted 95 on the plunger, a rod pivotally connected to said link and said locking member, respectively, at its opposite ends, the spring of said link tending constantly to force the locking member into locking position, and means carried by the car and adapted to 100 engage said link in the separating movement of the cars to turn the locking member to unlocked position.

4. In a train pipe coupler, a bracket supported on the car and having a rearwardly extending lug, a spring pressed plunger mounted in said bracket and having a coupler head pivotally mounted thereon at its forward end, a locking member pivotally 110 mounted on said head, a link pivotally mounted at the rear end of said plunger, a rod pivotally connecting said link and said locking member, and a spring exerting constant pressure on said link and tending normally to turn the locking member to locked 115 position and to maintain it in such position under spring pressure, said lug being adapted to engage the link in the separating movement of the cars whereby to throw the link backward and thereby turn the locking member to unlocked position.

5. In a train pipe coupler, in combination with a spring pressed plunger carried by the car and having a pivoted coupler head, locking mechanism comprising an intermediate 125 and two terminal pivotally mounted members, one of said members being a locking

member, a spring acting on the other member and tending normally to turn and maintain said locking member in a locked position, and means carried by the car and
5 adapted to engage said other member and to turn it against the resistance of its spring to release said locking member.

In testimony whereof, I have hereunto set my hand in presence of two subscribing witnesses.

PETER SCHMIDT.
